[57] ABSTRACT

A self contained, key operated, multiple station counting device suitable for use, for example, with a compacting device serving a number of users. Each user's station is provided with first key actuated means by which the trash compactor is actuated to receive, and then compact, trash placed therein, while at the same time a counting means is actuated to show this use of the compactor. Each user's station is further provided with second key actuated means by which a separate counter, restricted to its respective station, is actuated to show that the compactor was actuated from that station. In this way the total number of times the compactor is used during a given time period is recorded while at the same time this total is broken down to show how many such uses are attributable to each of the individual stations.

KEY OPERATED, MULTIPLE STATION
COUNTING DEVICE

BACKGROUND OF THE INVENTION

1. Field of the Invention

For a long time operators have needed a means by which they could determine who and how much trash a customer disposes of in their stationary compactors. This became more of a necessity for the operator with the advent of the large shopping centers, malls, multiple apartment complexes, large office buildings and some corporations who are wanting to know how much trash is being generated by various departments within their operation. The key operated, multiple station counting device allows multiple customers the use of one stationary compactor, centrally located in their operating area. The unit will name the customer, tell how much trash he disposes of and tell how often the compactor was used altogether.

2. Description of the Prior Art

No search of the records contained in the United States Patent Office has been made. It is believed that counting devices of some kind have been employed with duplicating machines located in certain offices so that the number of times various departments use a common duplicating machine can be determined. It is also believed that some sort of counting arrangements have been used in connection with fuel pumps. It is not known, however, how these other counting devices function.

SUMMARY OF THE INVENTION

The counting device has its own source of electric power. The trash compactor also has its own source of electric power. The trash compactor is normally in its closed or compacting position, that which it reaches at the end of its compacting stroke. The compactor and its control circuit, both of which are old and well known in the art, are arranged, for example, so as to include a normally closed switch. When this normally closed switch is opened, the compactor ram will retract to the open, trash receiving position for the compactor. When the switch is closed the compactor ram moves on its compacting stroke. Actuation of this normally closed switch is controlled by a relay which is in a circuit that includes a pilot light, the totalizer and all the top switches of all of the stations included in the device. When anyone of these top switches is actuated by the turn of a key and the associated cam, the pilot light is turned on, the totalizer tabulates another use of the compactor, and the relay opens the normally closed switch located in the power line for the compactor. When this key is returned to its original position the pilot light goes off and the relay permits the normally closed switch to return to its closed position whereby the compactor ram moves on its compacting stroke. The turn of the key also actuates another cam which operates the bottom switch for that particular station whereby the counter for that station is actuated so that the number of times the compactor was operated from that station is recorded. Each station has a similar circuit including its own bottom switch and counter.

BRIEF DESCRIPTION OF THE DRAWINGS

FIG. 1 is a diagrammatic, perspective view showing the key operated, multiple station counting device and the compactor utilized therewith and illustrating what

happens when the key is turned clockwise as indicated in this FIG.

FIG. 2 is a diagrammatic, perspective view similar to that of FIG. 1 and illustrating what happens when the key is returned to its original position by turning it in a counter-clockwise direction.

FIG. 3 is a fragmentary side elevational view, partly in section, illustrating one of the plurality of stations.

FIG. 4 is a perspective view of one of the plurality of stations.

FIG. 5 is a schematic diagram illustrating the circuit that is common to all of the top switches and which includes the pilot light, the totalizer, and the relay which controls actuation of the compactor.

FIG. 6 is a schematic diagram illustrating the circuits which are employed with each of the bottom switches, each such bottom switch having a connection to a separate counter.

DESCRIPTION OF THE PREFERRED
EMBODIMENT

Referring first to FIGS. 1 and 2 the key operated multiple station counting device is generally indicated at 10 and the compactor at 11. For purposes of illustration the counting device is shown as having 30 key operated stations 12. More or less of these stations may be included without departing from the scope of the invention. The ram 13 of the compactor 11 is normally closed. When one desires to use the compactor he places his key in his station 12 and turns it, this initial turn of the key being indicated as in a clockwise direction as seen in FIG. 1. Upon such turn of the key the ram 13 will move in the direction indicated in FIG. 1 so that trash may be deposited behind the ram 13 in the area indicated at 14. When the selected key is returned to its original position the ram 13 will return to its closed position on a compacting stroke whereby to compact the trash indicated at 15 in FIG. 2. It will be understood that this trash is compacted within a container, not shown, located in the compactor 11 so that the compacted, packaged trash may be removed from that end of the compactor which is opposite the ram 13 and taken to a dump or the like.

An individual station 12 is illustrated in FIGS. 3 and 4. Each such station 12 includes a U-shaped bracket 16 secured to a wall 17 of the counting device. A shaft 19 is suitably journaled within the bracket 16 and wall 17. The shaft is rotated by turning a key placed into mechanism, not shown in detail, located within the housing 20. The members 21 and 22 cooperate to this end in conventional manner. Suffice it to say that the key 18 may be turned from an off position to an on position and back again. The shaft 19 is thus rotated by these turns of the key. Such key operated mechanisms are conventional, being old and well known in the art.

A pair of micro switches 23 and 24 is fixed to the bracket 16 as indicated at 25. The micro switch 23 is more particularly designated as a bottom switch and the micro switch 24 as a top switch. These switches are normally open. Each may be closed by depressing its contact button 26 and 27 respectively. A pair of cams 28 and 29 is fixed on the shaft 19. In the off position of the key 18 the cams 28 and 29 are out of contact with the buttons 26 and 27. When the key 18 is turned from its off position to its on position, for purposes of illustration this has been indicated as a clockwise movement when considering FIG. 1, the shaft 19 is ro-

tated so as to bring the cams 28 and 29 into contact with the buttons 26 and 27 whereby to close the normally open, bottom and top micro switches 23 and 24. When the key 18 is returned from its on position to its original off position the cams 28 and 29 are moved out of contact with the buttons 26 and 27 whereby the top and bottom switches 23 and 24 respectively return to their open condition. All of this is conventional, old and well known in the art. Their specific incorporation, however, in the overall system described herein, is new.

Referring briefly to FIG. 5, the counting device is illustrated as operating on 120 volts alternating current from a source of electric power which, for purposes of illustration, is considered as including a hot line or wire 30 and a neutral wire 31. As shown in FIG. 4 the hot line 30 is connected to each of the bottom and top switches 23 and 24. This same hot line, or a continuation of it, will also be connected to all of the other micro switches provided for the other stations all of which are arranged in the manner indicated in connection with station 12 shown in FIGS. 3 and 4. Wires or lines leading from the switches 23 and 24 are indicated at 32 and 33. It will be understood that when the normally opened switches 23 and 24 are closed, electricity will flow through the hot line 30 to the respective lines 32 and 33 via the micro switches 23 and 24 as closed by actuation of the key operated cams 28 and 29.

FIG. 5 schematically depicts the circuit arrangement which includes the top switch 24. The hot wire 30 is illustrated as being connected to the terminal 34 of a terminal strip 35, there being a connection between the terminal 34 and a second terminal 36. The wire coming from the terminal 36 is a continuation of the hot wire 30 and, therefore, has been given the same reference numeral. This hot wire 30 is connected to the top switch 24 as earlier explained. (As will be shown in greater detail later, it is also connected to the bottom switch 23.)

The wire 31 which has been designated as a neutral wire is connected to the terminal 37 of the strip 35, there being a further connection between the terminal 37 and the terminal 38. The wire coming from the terminal 38 is also in effect a continuation of the neutral wire 31 and has been accorded the same reference numeral 31. A further terminal strip 39 is utilized. This strip 39 has a plurality of aligned, connected terminals disposed in a lower horizontal row. The neutral wire is connected to the first of these lower terminals. There is an upper row of corresponding terminals. Corresponding upper and lower terminals generally indicated at 41 and 42 are connected together. All of the terminals 42 are connected together but the terminals 41 are connected only to their respective, corresponding terminals 42. The terminal strip 49 must contain enough of the terminals 41 and 42 to provide one pair for the relay, one pair for the totalizer, and one pair for each of the bottom switches 23.

The relay is generally indicated at 43 and is illustrated as having 8 terminals numbered 1 through 8 as indicated. The relay itself is old and well known in the art and will not be described in detail. This is also true of the totalizer 44 and the pilot light 45. It should be noted that station No. 2 of the relay 43 is hot and the station No. 7 of the relay is neutral, there being, however, internal relay mechanism connecting these stations 2 and 7. The hot line 30 extending from the top switch 24 is connected to station 2 of the relay 43. The

neutral wire 31 coming from the terminal strip 39 is connected to station 7 of the relay 43. The line 30 has a continuation which includes the pilot light 45 and the line 31 has a continuation which also connects to the pilot light 45. The line 30 has a further continuation connecting to the totalizer 44 while the line 31 has a continuation, via the aligned, lower row of terminals in the terminal strip 39, which also includes the totalizer 44. There is a connection between the last of the upper terminals 41 and the last of the lower terminals 42, these being those indicated at the right-hand side of the strip 39 as viewed in FIG. 5. A similar connection exists between the furthermost left-hand upper and lower terminals 90 and 42.

When the top switch 24 is closed by turning a key as described earlier herein, a circuit is closed which includes the pilot light 45 via the hot wire 30, the switch 24, station No. 7 of the relay 43 and the neutral wire 31; at the same time the totalizer 44 is actuated via the hot line 30, station No. 2 of the relay 43, and the neutral wire 31; and the relay 43 is actuated by the hot line 30, station No. 2 of the relay, the internal mechanism (not shown) of the relay, station No. 7 of the relay and the neutral line 31. In effect, a single circuit accomplishes all of the foregoing. All of the top switches utilized will be located in this circuit in the same manner as described in connection with top switch 24 of FIGS. 3 and 4. Thus, if the counting device includes 30 of the stations 12, each of the 30 top switches will be located in the circuit just described in the same manner as the particular station 24 shown. As an example, a second top switch 24 has been shown in FIG. 5. Actuation of any one of these top switches 24 will complete the circuit that turns on the pilot light, activates the relay and actuates the totalizer.

Considering FIGS. 1, 2 and 5, the compactor 11 has its own source of electric power and includes a hot line 50 and a neutral line 51. The lines 50 and 51 are connected to the compactor 11 in such manner that the ram 13 is normally in its closed position when the circuit 50, 51 is intact. A normally closed switch 53 having terminals A and B is included in the circuit 50, 51. The stations A and B are respectively connected to stations 3 and 6 of the relay 43 by lines 54 and 55. The compactor circuit 50, 51 includes an arrangement generally indicated at 60 which is effective to move the ram 13 to its open position when the switch 53 is opened to break the compactor circuit 50, 51.

The internal mechanism of the relay 43 is so arranged that when station No. 2 gets hot as will happen when any one of the top switch 24 is closed, the stations 3 and 6 of such relay will become active and a circuit completed through the lines 54 and 55 to connect the stations A and B and open the switch 53. When the switch 53 opens the circuit 50, 51 is broken and, due to the internal workings of the mechanism 60, the ram 13 will move to its retracted or open position. It should be noted at this point that various control systems are used in connection with compactors and this invention is not directed to the specific operation of the compactor as such. Such compactors and the means for operating them are old and well known in the art.

It will be observed, therefore, that when any one of the top switches is closed, a master circuit is put in operative condition and this circuit includes the pilot light 45, the totalizer 44 and the relay 43 which includes in turn leads 54 and 55 connected to the switch 53 lo-

cated in the compactor circuit whereby actuation of such relay 43 opens the switch 53 to permit the compactor to open whereby trash may be placed in the charge chamber 14 indicated in FIG. 1.

FIG. 6 illustrates a circuit for a bottom switch and its counter. Wherein those devices and circuit members respond to those previously described, like reference numerals will be employed. Thus, for example, note that the 120 volt alternating current source includes the same hot line or wire 30. This further illustrates the fact, mentioned earlier, that both the top and bottom switch of each station are all heated up from the same electric power source. Extensions of the hot line 30 extend to and from the bottom switch 23. The micro switch 23 is normally open. When the contact button 26 is actuated by its cam the circuit through the bottom switch 23 is completed. The extension 30 leading from the switch 23 connects to a terminal located on a terminal strip 70. The neutral wire 31 extends from the terminal strip 35 to the terminal strip 39. The extension 31a of this neutral wire 31 takes off from the terminal 41 for counter No. 1 to the counter 72, the extension 31a then hooking up with the terminal strip 70.

When the bottom switch 23 is closed it will be seen that there is a closed circuit including the hot line 30, the counter 72 and the neutral line 31 and extension 31a thereof. All bottom switch circuits will be like the one illustrated. Although the hot line 30 will heat up all of the bottom switches, as well as all of the top switches, there will be a separate circuit for each of the bottom switches and their respective counters, thus the plurality of stations on the terminal strip 39. For purposes of illustration the counter 80 for a second station 12 has been shown in the circuit which includes its bottom switch 23a. Counter 72 is connected to station No. 1 on the terminal strip 39 while counter 80 is connected to the connector strip 39 at terminal No. 2. The most left-hand terminal on the strip 39, as viewed in FIGS. 5 and 6, is terminal 90 for the relay discussed earlier herein.

In the preferred form of the invention, as generally indicated in FIGS. 1 and 2, there will be 30 of the stations 12 shown in FIGS. 3 and 4. There will be 30 pairs of top and bottom switches 24 and 23. All 60 of the switches will be heated up from the same 120 AC source. The 30 top switches 24 will be in a single circuit which includes the hot line 30, the top switches 24, the pilot light 45, the totalizer 44, and the relay 43. Although all 30 of the bottom switches 23 will also be heated up by the hot wire 30, there will be separate, but like, circuits connecting each bottom switch with its respective counter, thus, for example, one such circuit will include the hot line 30, the bottom switch 23 and the counter 72. Another such circuit will include the hot line 30, the bottom switch 23a, and the counter 80. A third bottom switch (not shown) would be connected through its counter to others of the terminals 41 and 42 on the strip 39; this would be for station No. 3. It will be understood that additional terminals and counters will be supplied to take care of all of the stations incorporated in the device which, as shown herein, would amount to 30 such stations.

It will be noted that all of the top switches 24 do the same job, namely, each will actuate the pilot light 45, the totalizer 44 and the relay 43 which in turn will control actuation of the compactor; all of these switches 24, therefore, are in the same circuit. All of the bottom

switches 23 and the circuits which include the respective counters are like but separate in that there is a separate connection between each bottom switch 23 and its counter for that station 12.

By way of review, the key operated, multiple station counting device contains a plurality of the stations 12, 30 being illustrated in the embodiment described herein. Each station has a pair of micro switches 24 and 23, the top and bottom switches herein discussed. Each 10 station has a pair of cams 29 and 28 which are located on a shaft 19 which may be rotated by means of a key 18. Each station 12 will be actuatable by a separate and distinctive key 18. Each customer will be assigned a particular station 12 and given the particular key 18 for actuating that station.

When a customer desires to make use of the compactor he will go to the counting device, insert his key in the respective housing 30 for the station 12 assigned to him, and actuate the shaft 19. When this is done the top 20 and bottom switches 24 and 23 for that station are actuated. The closing of the bottom micro switch 23 will complete a circuit through the counter assigned to that station thus showing the number of times that the compactor was operated via that station. The closing of the top micro switch 24 will turn on the pilot light, thus indicating the system to be in working order, it will actuate the totalizer, thus showing the total number of times the compactor is operated by all of the stations, and the relay which controls the compactor 11 will be activated. When so activated the compactor ram 13 will move from its normally closed position to an open position at which time the charge chamber 14 is available to receive trash. When the selected key 18 is returned to its original position, the circuits which include the top and bottom switches will be opened and deactivation of the relay 43 will permit the separate power circuit 50, 51 for the compactor 11 to again close whereby the compacting ram 13 returns to its closed position while compacting the trash placed within the charge chamber 14.

It will be apparent to those skilled in the art that modifications may be made in this invention without departing from the scope and spirit thereof. While the invention has been shown and described in connection with particular devices and circuits, these are not to constitute a limitation on the invention except in so far as they are specifically included in the subjoined claims.

The embodiments of the invention in which an exclusive property or privilege is claimed are defined as follows:

1. A system for counting the number of times a trash compactor is used and by whom including a trash compactor having a normally closed position and a first source of electricity for actuating said compactor; a counting device having a second source of electricity; a plurality of stations in said counting device; a pair of normally open first and second switches for each said station; actuating means at each station for closing and opening said first and second switches together, a first circuit connected to said second source and including all of said first switches; a relay in said first circuit having an operative connection to said first source whereby to control actuation of said compactor; a totalizer in said first circuit for counting the total number of times said relay is actuated; a plurality of like second circuits connected to said second source, there being a

separate said second circuit for each said second switch; a plurality of counters, there being one said counter in each said second circuit for counting the number of times said relay is actuated from the selected said station; and a plurality of dissimilar keys, one for each said station, to engage the said actuating means at the said station selected; whereby when said selected key is turned to move said actuating means the said first and said second switches for the selected station are closed and said relay, said totalizer and the said counter for the selected station are actuated, actuation of said relay causing said compactor to open so that trash may be placed therein, said totalizer and the said selected

counter each recording such actuation of the said relay and said compactor, and whereby when said key is turned to its original position the said first and said second switches for the selected station are open and said relay, said totalizer and the said counter for the selected station are deactivated, deactivation of said relay causing said compactor to return to its original closed position whereby to compact the trash placed therein when open.

2. The system of claim 1 including a pilot light in said first circuit.
